[57] CLAIM

The ornamental design for a drawer for a cassette cabinet or similar article, as shown and described.

DESCRIPTION

FIG. 1 is a perspective view of a drawer for a cassette cabinet or similar article, showing my new design;

FIG. 2 is a top plan view;

FIG. 3 is a bottom plan view;

FIG. 4 is a rear elevational view;

FIG. 5 is a side elevational view, the opposite side being a mirror image thereof;

FIG. 6 is a perspective view of a drawer for a cassette cabinet or similar article, showing a second embodiment of my new design;

FIG. 7 is a side elevational view of the second embodiment, the opposite side being a mirror image thereof;

FIG. 8 is a bottom plan view of the second embodiment;

FIG. 9 is a perspective view of a drawer for a cassette or similar article, showing a third embodiment of my new design;

FIG. 10 is a side elevational view of the third embodiment, the opposite side being a mirror image thereof; and

FIG. 11 is a bottom plan view of the third embodiment.

FIG. 2

FIG. 3.

FIG. 4.

FIG. 5.

FIG. 7.

FIG. 8.

FIG. 9.

FIG. 10.

FIG. 11.
